LOCOMOTIVE BODY OR THE LIKE

Ray Patten, Norwalk, Conn., assignor to General
Electric Company, a corporation of New York

Application August 28, 1946, Serial No. 132,913

Term of patent 3½ years

(Cl. D66—1)

To all whom it may concern:

Be it known that I, Ray Patten, a citizen of the United States, residing at Norwalk, in the county of Fairfield, State of Connecticut, have invented a new, original, and ornamental Design for a Locomotive Body or the like, of which the following is a specification, reference being had to the accompanying drawings, forming a part thereof.

In the drawings, Fig. 1 is a fragmentary perspective view of the instrument panel section of my design; Fig. 2 is another fragmentary perspective view shown from another angle and both being on a somewhat enlarged scale, and Fig. 3 is a side elevational view of a locomotive body embodying a control panel and in accordance with my new design. The characteristic features of my design reside in the portions shown by full lines in the drawing and especially as set forth in Figs. 1 and 2.

I claim:

The ornamental design for a locomotive body or the like, substantially as shown and described.

RAY PATTEN.
